LLP

(57) **CLAIM**

The ornamental design for a spectacle case, as shown and described.

DESCRIPTION

FIG. 1 is a top perspective view of a spectacle case, showing our new design in a closed configuration;

FIG. 2 is a top plan view thereof;

FIG. 3 is a bottom plan view thereof;

FIG. 4 is a left side elevational view thereof, the right side being a mirror image thereof;

FIG. 5 is a front elevational view thereof;

FIG. 6 is a rear elevational view thereof;

FIG. 7 is a top perspective view of the spectacle case of FIG. 1 in an open configuration;

FIG. 8 is a top plan view thereof;

FIG. 9 is a front elevational plan view thereof; and,

FIG. 10 is a right side elevational view thereof, the left side being a mirror image thereof.

1 Claim, 10 Drawing Sheets
